UNITED STATES PATENT OFFICE.

AUGUST G. JOHNSON, OF MONESSEN, PENNSYLVANIA.

DESIGN FOR A WIRE FENCE.

59,119.

Specification for Design. Patented Sept. 20, 1921.

Application filed October 24, 1918. Serial No. 259,590. Term of patent 14 years.

To all whom it may concern:

Be it known that I, AUGUST G. JOHNSON, a citizen of the United States, residing at Monessen, county of Westmoreland, State of Pennsylvania, have invented a new, original, and ornamental Design for Wire Fences, of which the following is a specification, reference being had to the accompanying drawing, forming part thereof.

The figure is a view in elevation of a por-

tion of a wire fence illustrating my new design.

I claim:

The ornamental design for a wire fence, as shown.

AUGUST G. JOHNSON.
